DESIGN FOR METAL MESH FABRIC

Charles A. Whiting, Franklin, Mass., assignor to
Whiting & Davis Company, Plainville, Mass., a
corporation of Massachusetts

Application August 1, 1935, Serial No. 57,897

Term of patent 14 years

To all whom it may concern:

Be it known that I, Charles A. Whiting, a citizen of the United States, residing at Franklin; Norfolk County, Massachusetts, have invented a new, original, and ornamental Design for Metal Mesh Fabric, of which the following is a specification, reference being had to the accompanying drawing, forming part thereof.

Figure 1 is a plan view of a section of metal mesh fabric showing my new design.

Figure 2 is an enlarged cross-sectional view of one of the links connected to the adjacent rings shown in Figure 1.

I claim:

The ornamental design for metal mesh fabric as shown and described.

CHARLES A. WHITING.
